INSPECTION ARRANGEMENT FOR AN AUTOMATIC SEWING APPARATUS

Paul Schwendinger, Wiesental, Germany, assignor to Spinnerei und Webereien Zell-Schönau Aktiengesellschaft, Zell, Germany, a corporation of Germany

Filed Nov. 10, 1964, Ser. No. 410,232

Claims priority, application Germany, Nov. 11, 1963, S 88,237

1 Claim. (Cl. 209—74)

This invention relates to automatic inspection of work pieces, and particularly to an automatic arrangement for inspecting work pieces produced on a conveyorized automatic sewing apparatus, and for rejecting defective pieces.

Defects in work pieces in the apparatus discussed are generally of two kinds. They may be optically ascertainable defects such as misweaves, spots, and visible defects, and they may be defects caused by malfunctioning of the working implements of the apparatus such as a missing seam due to breakdown of a sewing head which are not readily detected by optical devices. Malfunctioning of a working implement, however, is readily detected by means other than optical devices, particularly by sensing means arranged in the electrical drive circuits of the working implements.

An object of the invention thus is the provision of an inspecting and sorting arrangement for automatic sewing apparatus and the like which responds to both afore-described types of defects in the work pieces processed.

Other objects and features of the invention will become apparent to those skilled in the art as the disclosure is made in the following detailed description of a preferred embodiment of the invention as illustrated in the accompanying drawing in which:

FIG. 1 is a plan view of a memory device employed in the inspection arrangement of the invention;

FIG. 2 shows the sorting station of an automatic sewing apparatus which is controlled by the memory device of FIG. 1 in front elevation; and

FIG. 3 is a fragmentary side elevational view, partly conventional, of the automatic sewing apparatus.

Referring now to the drawing, and initially to FIG. 1, there is seen a disk 1 on the periphery of which twelve signaling rods 2 are slidably mounted at uniform angular distances. The rods are arranged for radial movement in respective bearings on the disk 1, and are retained in their radial positions by frictional engagement with the bearings. Ten solenoids 3 are fixedly mounted about the circumference of the disk 1 in respective positions A to K which are radially aligned with ten of the twelve rods 2 in the illustrated position of the apparatus. When a solenoid is energized, as shown in position F, an abutment 4 on the armature of the solenoid engages the aligned rod 2 and pushes it radially inward from the normal position illustrated by all other rods.

The disk 1 is indexed about its axis by a mechanism which includes a solenoid 5, a crank rotatably supported on the non-illustrated shaft of the disk 1, connecting rod 6 attached to the armature of the solenoid 5 and the crank, a pawl 7 mounted on the crank, and a ratchet 8 cooperating with the pawl 7 and connected to the disk 1 for joint movement by the common, non-illustrated shaft. When the solenoid 5 is briefly energized, the disk 1 is indexed 30° about its axis into a position in which again ten rods 2 are radially aligned with the ten solenoids 3 and their abutments 4.

A pulse or electrical signal received by one of the solenoids 3 is thus recorded on the disk 1 by displacement of one of the rods 2 which constitute the memory elements of the illustrated device. The recorded signal is read by a device consisting of an electric light bulb 9, a

2

mirror 13, and a photoelectric cell 10. After passing through positions A to K during the clockwise movement of the disk 1 indicated by an arrow, each rod 2 reaches a reading position free from a solenoid 3. The reading device is arranged in such a manner that the light beam from the light bulb 9 to the mirror 13 is intercepted by a rod at the reading position if it is in its normal position. If the rod is inwardly displaced in the manner shown at F, the light beam from the bulb 9 is reflected from the mirror 13 on the photoelectric cell 10.

A stationary disk 11 coaxial with the stationary disk carries a cam 12 arranged after the reading position of the rods to return an inwardly displaced rod 2 to its normal position during rotation of the disk 1. The output terminals of the photoelectric cell 10 are connected to a motor switch 14.

FIG. 2 shows the sorting station of the automatic sewing apparatus which is controlled by the memory device of FIG. 1. A finished work piece 15 is supported on a conveyor belt 16 which is trained over several pulleys including a drive pulley 19. Rotation of the pulley 19 is energized by an electrically reversible motor 17 connected to the pulley 19 by a belt 18. The motor is controlled by the afore-mentioned motor switch 14 in such a manner that it moves the belt 16 in the direction of the arrow 21 when the photoelectric cell 10 is shaded by a rod 2, and moves the belt 16 in the direction of the arrow 22 when the photoelectric cell receives a beam of light from the bulb 9. Depending on the direction of belt movement, the work piece 15 is moved toward storage areas 20 and 20' for acceptable and rejected work respectively.

FIG. 3 shows a portion of the automatic conveyorized sewing apparatus sufficient for an understanding of the invention. Work pieces are carried on a conveyor belt

35 past a sewing head 26 at one of the conveyor stations. Belt movement is intermittently actuated by a drive shaft 27 on which a pulley 28 carrying the conveyor belt is mounted. An idler pulley 29 which is driven by the moving conveyor belt carries a centrifugal switch 30. The switch is arranged in circuit with a current source 31 and the solenoid 5 to energize the solenoid during each conveyor movement.

The sewing head 26 is equipped with an internal switch, not shown, which interrupts the current supply to the electric drive motor of the sewing head when the sewing thread 32 breaks. A zero-current relay 33 in the supply circuit of the sewing motor generates an electrical pulse upon interruption of the current. This pulse is transmitted to the solenoid 3 of the memory device associated with the work station at which the sewing head 26 is installed.

A spot light 34 illuminates the working area of the sewing station and a work piece located there. A conventional photoelectric sensing apparatus 35, not shown in detail, is trained on the working area and generates yet another signal in response to an optically ascertainable defect in a work piece at the station, the signal being transmitted to the associated solenoid 3 for energizing the same.

While only one working and inspection station has been illustrated in FIG. 3, it will be appreciated that other stations will normally be arranged along the path of the work piece on the conveyor, each station being equipped with signal generating means responsive either to a sensed defect of the work piece or to malfunctioning of the working implement installed at the station, and connected to an associated solenoid 3 of the memory device illustrated in FIG. 1. The illustrated memory device is intended for use with 12 stations of which 10 are equipped to generate signals.

After passing the several working and inspecting stations, the work piece is transferred to the conveyor belt

16 of the sorting station not otherwise shown in FIG. 3, and described in more detail hereinabove with reference to FIG. 2.

Obviously, many modifications and variations of the present invention are possible in the light of the above 5 teachings. It is therefore to be understood that, within the scope of the appended claim, the invention may be practiced otherwise than as specifically described.

What is claimed is:

An automatic working and inspecting arrangement 10 comprising, in combination:

- (a) conveyor means for conveying a work piece in a predetermined direction between a plurality of stations;
- (b) working means arranged at one of said stations 15 for working said piece;
- (c) first signal generating means at said one station for sensing a defect in the conveyed piece and for generating a signal in response to the sensed defect;
- (d) second signal generating means connected to said working means for generating a signal in response to malfunctioning of the same;
- (e) sorting means at another one of said stations spaced from said one station in said direction;
- (f) a memory element; 25
- (g) signal recording means connected with said first and second signal generating means and alignable

with said memory element for recording the generated signals on said memory member when aligned therewith;

- (h) signal reading means alignable with said memory element for reading a recorded signal,

(1) said sorting means being operatively connected to said signal reading means for rejecting said work piece at said other station in response to the read signal; and

- (i) actuating means for actuating simultaneous movement of said work piece from said one station to said other station and of said memory element from a position of alignment with said signal recording means to a position of alignment with said signal reading means.
